DESIGN FOR A FISHING ROD

Application filed December 30, 1929. Serial No. 33,984. Term of patent 14 years.

To all whom it may concern:

Be it known that we, EDWARD J. BRYER and CHARLES H. PIERCE, residing at Kalamazoo, in the county of Kalamazoo and State of Michigan, have invented a new, original, and ornamental Design for a Fishing Rod, of which the following is a specification, reference being had to the accompanying drawing, forming part thereof.

Fig. 1 is a fragmentary side view of a fishing rod showing our new design.

Fig. 2 is an enlarged fragmentary perspective view, and

Fig. 3 is an enlarged fragmentary side view. The cross hatching in the drawing indicates color.

We claim:

The ornamental design for a fishing rod, as shown.

EDWARD J. BRYER.
CHARLES H. PIERCE.
